DESIGN FOR A CALCULATOR

Arnold H. Mueller, Monroe, Wis.

Application March 15, 1945, Serial No. 118,499

Term of patent 3½ years

(Cl. D52—1)

To all whom it may concern:

Be it known that I, Arnold H. Mueller, a citizen of the United States, residing at Monroe, in the county of Green and State of Wisconsin, have invented a new, original, and ornamental Design for a Calculator, of which the following is a specification, reference being had to the accompanying drawing, forming part thereof.

The figure is a perspective view of a calculator, showing my new design, the rear surface of the calculator being substantially of the appearance of the side shown.

I claim:

The ornamental design for a calculator, as shown and described.

ARNOLD H. MUELLER.
